RETURN BEND FOR CRACKING COILS IN
OIL STILLS

Fred C. Fantz, Webster Groves, Mo.

Application February 15, 1933, Serial No. 656,798

3 Claims. (Cl. 285—20)

My invention relates to that class of return bends, in which the housing therefor is formed in sections and has for its principal object to provide an improved construction for the housing. It is well known that the industry is recognizing the fact that the rolled in tube is no longer to be considered the best type of attachment for the housing to connect the return bend to the end of the tube, and tubes with upset shoulders, which are demountably mounted in housings, are rapidly coming into use.

This being largely due to the fact that it is highly desirable in view of the fact that the refiners are being forced to higher pressures and higher temperatures by the demands of the trade that the tubes be demountably mounted in the still so that they can be removed for inspection or replacement or moved to a less hazardous portion of the still or turned over in the event that they bow or sag from the heat and pressure which is a constant occurrence.

A further object of my invention is to provide a demountable housing for the tube which will not require any sectional or other bushings to be mounted intermediate the housing and the still tubes.

My means of accomplishing the foregoing objects may be more readily understood by having reference to the accompanying drawings which are hereto annexed and are a part of this specification, in which—

Fig. 1 is a side elevation of my improved device, a portion of the wall of the housing being broken away to show the manner in which the tubes are mounted inside of it;

Fig. 2 is a top or plan view of the same, the U or return bend being omitted;

Fig. 3 is an end view of my device as shown in Fig. 1; and

Fig. 4 is a section on the line 4—4 in Fig. 1, the U or return bend being omitted for clearness. Similar reference numerals refer to similar parts throughout the entire description.

As shown in the drawings, a conventional return bend 1 is provided to connect a pair of adjacent still tubes 2 and 3. These tubes are provided with external shoulders 4 which may be formed by upsetting the tubes in the usual manner. The return bend 1 is mounted inside of a sectional housing formed in two parts 5 and 6. The housing is provided with upwardly extending side walls 7 and 8 which are arcuate in cross section and are preferably provided with circumferential slots 9 adjacent their upper ends in which are mounted toggles 10 which carry set screws 11, the inner

ends of which are adapted to engage abutments 12 formed on the external surface of the return bend 1.

The outer portions of the arcuate upwardly, extending side walls 7 and 8 are provided with lugs 13 and 14 which abut and which are provided with passageways which extend therethrough. In these passageways I mount suitable securing pins 16 which may, if desired, be secured in place by means of cotter pins 15, as shown in Fig. 2, the left hand pin is removed.

It will be apparent to persons skilled in the art that when these pins are inserted into the openings to which they are fitted that the housing will be to all intents and purposes a one piece housing and the internal shoulders 17 will abut the shoulders 4 formed on the tubes 1 and 2 so that by tightening the set screws 11 in the toggles 10 the return bend will be forced into a tight joint with the ends of the tube.

Additional securing means for locking the halves together may be provided. In the detail view, Fig. 4, I have shown one form in which I provide a saddle 20 which is provided with inclined walls which are adapted to engage correspondingly inclined walls 21 formed on the halves 5 and 6 of the housing. By tightening the screw 22, it will be apparent that the central portions of the housing will be drawn tightly together and securely locked.

From the foregoing description it will be apparent, unless the additional lock is employed, that all that is necessary to do is to remove one of the pins 16 when the housing can be swung on the pin at the other end of the housing which will operate to disengage the annular shoulders from the upset portions of the tube and the housing can be easily removed. At the same time if all that is necessary to do it to remove the return bend so as to gain access to the interior of the tubes for cleaning purposes, this can be done without removing either of the pins 16 or the saddles 20 and the housing will be practically a one piece housing which will serve to hold the tubes in alignment so that the return bend can be replaced without difficulty and a tight joint secured.

It will be apparent from the foregoing description that if desired, both pins may be withdrawn and the halves lifted apart. It may also be found desirable in this construction to provide for the clearance shown in my Patent No. 1,874,003. This will permit closer nesting of the tubes.

Having described my invention what I regard as

new and desire to secure by Letters Patent is:

1. In a refinery apparatus, a conventional return bend adapted to connect a pair of shou-
dered still tubes to provide a continuous pas-
sageway therethrough, a housing for said return
bend formed in halves, lugs at the outer end of
said housing, a hinge pin mounted therein, de-
tachable means to lock the other ends of said
housing, arcuate shoulders on said halves, which
engage the shoulders on the tubes when the hous-
ing is closed, upwardly extending side walls on
said housing, detachable means mounted there-
in to draw the bend and the tubes into a tight
joint.
- 15 2. In a refinery apparatus, a conventional re-
turn bend adapted to connect a pair of shou-
dered still tubes to provide a continuous passage-
way therethrough, a housing for said return bend
formed in halves, lugs at the outer end of each
20 half of said housing, hinge pins mounted therein,

arcuate shoulders on said halves which engage
the shoulders on the tube when the housing is
closed, upwardly extending side walls on said
housing, detachable means mounted therein to
draw the bend and tubes into a tight joint.

3. In a refinery apparatus, a conventional re-
turn bend adapted to connect a pair of shou-
dered still tubes to provide a continuous pas-
sageway therethrough, a housing for said return
bend formed in halves, lugs at the outer end of
said housing, a hinge pin mounted therein, de-
tachable means to lock the other end to said
housing, arcuate shoulders on said halves which
engage the shoulders on the tubes when the
housing is closed, upwardly extending side walls on
said housing, detachable means mounted there-
in to draw the bend and tubes into a tight
joint, means mounted intermediate said tubes
to secure and lock said halves together.
